UNITED STATES PATENT OFFICE

DANIEL F. MCKINNON, OF BOSTON, MASSACHUSETTS

DESIGN FOR A WATERPROOF COVER FOR CAPS

Application filed February 13, 1931. Serial No. 38,640. Term of patent 14 years.

To all whom it may concern:

Be it known that I, DANIEL F. MCKINNON, a citizen of the United States, residing at Boston, in the county of Suffolk and the State of Massachusetts, have invented a new, original, and ornamental Design for a Waterproof Cover for Caps, of which the following is a specification, reference being had to the accompanying drawings, forming part thereof.

proof cap cover according to the present design.

Figure 2 is a side view of the same. Opposite side of water-proof cover for caps is the same as that illustrated.

I claim:

The ornamental design for a waterproof cover for caps, as shown and described.

DANIEL F. MCKINNON.
